UNITED STATES PATENT OFFICE.

JOSEF KEILER, OF MUNICH, GERMANY.

COLLAPSIBLE FRAME FOR FLOATING STRUCTURES.

1,108,076.

Specification of Letters Patent.

Patented Aug. 18, 1914.

Application filed May 20, 1914. Serial No. 839,710.

To all whom it may concern:

Be it known that I, JOSEF KEILER, teacher of swimming, a subject of the Emperor of Germany, residing at 2 Weissenburgerplatz, 5 Munich, Germany, have invented new and useful Improvements in Collapsible Frames for Floating Structures, of which the following is a specification.

The present invention relates to an improved construction of collapsible frames which are used for floating structures such as boats, water-skates and the like.

According to the invention the frame, 15 which is preferably of a prismatic shape, is made of rings and beams connected in such a manner that the frame may be collapsed for the purposes of transport without disconnecting the beams from the rings by the mere act of turning the rings and beams into 20 practically one plane.

In the accompanying drawings is shown a construction of the improved frame which is particularly suitable for so-called kayaks.

Figure 1 is a longitudinal section of the frame showing same in operative position, Fig. 2 is an enlarged fragmentary section on the line C D of Fig. 4 showing the front pointed portion of the frame in expanded position, and Fig. 3 is another enlarged fragmentary section on the line C D of Fig. 4 but showing the front pointed portion of the frame in the collapsed position. Fig. 4 is a plan of Fig. 1, Fig. 5 a section on the line A B of Fig. 1 and Fig. 6 is a section of 35 a hinge.

The rings 2 which are preferably made of wood and of a circular shape, are hinged to a bottom beam 1 and are connected at the top to top beams 3 and 4 by means of similar 40 hinges. The side beams 5 and 6 are pivotally fixed to the rings by means of bolts or rivets. The hinges by means of which the rings are connected to the top and bottom beams are of the construction shown in Fig. 45 6, and consist of yokes 7 fixed to the beams by means of screws or rivets. To limit the movement of the rings with regard to the beams when the frame is set up for use, the rings may be provided with bolts 9, sliding 50 in slots 8 of the yokes, the slots extending only over part of the circumference of the yokes as shown in Fig. 6.

Upon the bottom or keel beam 1 are 55 mounted two transverse bars 10 and 11 which carry a collapsible seat 12 made of

wooden slats. The hinged seat back 13 prevents, when the frame is used, the collapsing of the structure; the pressure upon the back tending to keep the structure in the position shown in Fig. 1. Around the beams and 60 rings, cords or wires may be wound in the usual manner in order to support the outer impermeable cover not shown in the drawings. The rear end of the structure is preferably made square while the front end is 65 made as pointed as possible for the purpose of reducing the resistance. In order to enable the pointed front part of the structure to be collapsed without disconnecting the component parts, the frame bars 15 and 16 70 are adapted to slide in grooves 17 and 18 of the beams 4 and 1, so that when the frame is collapsed, the bar 15 slides into the groove 17 while the bar 16 slides out of the groove 18 as shown in Fig. 3. If the frame is to be 75 used for a water-skate, an adjustable shoe 19 is fixed to the keel beam and the collapsing of the structure is prevented by means of a strut 20 fixed to the rear ring.

It may be pointed out that the above described collapsible frames may be used for almost any kind of floating structures, for instance, for water-skates, water cycles, water sledges, kayaks, floats for floating bridges, saving boats and the like. 80 85

I claim:

1. A collapsible frame for floating bodies, comprising a plurality of beams, and a plurality of normally transverse rings hingedly secured to said beams at two diametrically 90 opposite points and adapted, when the said frame is collapsed, to lie in substantially one and the same plane.

2. A collapsible frame for floating bodies, comprising a plurality of beams, a plurality 95 of rings hingedly secured to said beams at two diametrically opposite points, and adapted, when the said frame is collapsed, to lie in substantially one and the same plane, and means for supporting said frame when 100 in the non-collapsed position.

3. A collapsible frame for floating bodies comprising a plurality of beams connected together by means of rings, certain of said beams being connected to said rings by 105 means of hinges which are arranged in the lateral direction.

4. A collapsible frame for floating bodies comprising top and bottom beams, side beams, and a plurality of rings pivotally 110

mounted on said side beams and connected to said top and bottom beams by means of hinges, substantially as described.

5. A collapsible frame for floating bodies comprising top and bottom beams provided with grooves at their front ends, side beams projecting beyond said top and bottom beams, bars connected to the projecting point of said side beams and sliding in said 10 grooves in the top and bottom beams, and rings pivotally mounted on said side beams and connected by means of hinges to the top and bottom beams.

6. A collapsible frame for floating bodies, comprising top and bottom beams, side

beams, a plurality of rings pivotally mounted on said side beams and connected to said top and bottom beam by means of hinges, and a slideable forward frame section, adapted to be brought into the collapsed or non-collapsed position by the operation of the coacting parts comprising the main portion of the frame.

20 In testimony whereof I have signed my name to this specification in the presence of 25 two subscribing witnesses.

JOSEF KEILER.
